UNITED STATES PATENT OFFICE.

DONALD BARNS MORISON, OF HARTLEPOOL, ENGLAND.

APPARATUS FOR WITHDRAWING AERATED VAPOR AND CONDENSATE FROM STEAM-CONDENSERS.

1,155,951.

Specification of Letters Patent.

Patented Oct. 5, 1915.

Application filed September 2, 1914. Serial No. 859,920.

To all whom it may concern:

Be it known that I, DONALD BARNS MORISON, a subject of the King of Great Britain and Ireland, residing at Hartlepool, in the county of Durham, England, have invented Apparatus for Withdrawing Aerated Vapor and Condensate from Steam-Condensers, of which the following is a specification.

This invention relates to apparatus of the kind described and referred to in the specification of application Serial No. 859481 wherein aerated vapor is withdrawn from a steam condenser by a steam jet and is discharged into a receiver into which a regulated quantity of boiler feed water is admitted for the purpose of condensing the steam from the steam jet, the heated water being withdrawn from the receiver separately at a higher temperature than the aerated vapor, the air pressure or air density of the aerated vapor being increased by the condensation of the vapor by another portion of the boiler feed water of a temperature lower than that discharged from the receiver, thus decreasing the volume of a given weight of air and reducing the size of the air pump and the power necessary to discharge the air to the atmosphere.

The system according to the present invention may be applied to surface or jet condensers, and consists in withdrawing the aerated vapor and heated water from the receiver into which the steam jet discharges by one or more reciprocating pumps in the manner described in the specification hereinbefore referred to, the condensate from the condenser being withdrawn separately by a rotary pump.

A feature of the invention is that apparatus for artificially cooling the water which condenses and cools the aerated vapor, is not required, therefore there are no dangers resulting from leaks such as may occur with artificially cooled water in which the cooling agent is sea water. Moreover, the weight and space occupied are reduced, or alternatively, if the size of the pumps is maintained the number of strokes per minute can be reduced, thus reducing wear and tear.

The accompanying drawing Figures 1, 2 and 3, illustrates various forms of apparatus according to my invention, the same letters of reference being used to denote the similar parts in the several figures.

Aerated vapor is withdrawn from the condenser *c* by a steam jet device *s* discharging into the receiver *r*, a regulated quantity of boiler feed water being admitted through the valve *g* into the receiver *r* in which it condenses the steam from the steam jet device *s*. The heated water is withdrawn from the receiver *r* separately through the pipe *e* and the aerated vapor is withdrawn through the pipe *f*, and *f'* in Fig. 3, in which pipes the air pressure of the aerated vapor is increased by the condensation of the vapor by another portion of the boiler feed water admitted through the valve *h*, and *h'* in Fig. 3.

In Fig. 1, a single air pump *a* is employed, the aerated vapor being withdrawn from the receiver *r* through the pipe *f* connected to the end of the barrel of the pump *a* below the piston, the heated water being delivered from the receiver *r* through the pipe *e* into the end of the barrel of the pump *a* above the piston. The condensate, and it may be the cooling water when the condenser *c* is of the direct contact type, is withdrawn from the condenser by the pump *m* which discharges through the pipe *n*, a portion of the water being delivered through the pipe *t* into the receiver *r* and pipe *f*.

In Fig. 2, separate pumps are employed for withdrawing the aerated vapor and heated water from the receiver *r*, the pump *a* withdrawing the aerated vapor through the pipe *f* and the pump *b* withdrawing the heated water by way of the pipe *e* in the manner shown in the drawing. The condensate, and it may be the cooling water from the condenser *c*, is removed separately in the manner hereinbefore described by the pump *m*.

Fig. 3 is a modification of Fig. 1 and in which two pumps *a* and *b* are employed for withdrawing the aerated vapor and heated water from the receiver *r*, the heated water

being delivered through the pipe *e* into the ends of the barrels of both pumps above the pistons, and the aerated vapor delivered through the pipes *f* and *f'* into the ends of 5 the barrels of both pumps below the pistons.

What I claim and desire to secure by Letters Patent is:

1. Apparatus for withdrawing aerated vapor and condensate from steam condensers, comprising a steam jet device in communication with a condenser, a receiver, a passage leading from the steam jet to the receiver, means for withdrawing aerated vapor and water separately from said receiver, said means comprising reciprocating pumps, a passage leading from the lower portion of the receiver to one end of one of said reciprocating pumps, and a passage or 10 passages leading from the receiver to one of the remaining ends of said reciprocating pumps, a pump connected to the condenser, and a passage for conveying water discharged from said pump to the passage or 15 passages last mentioned and to said receiver, the whole as and for the purpose hereinbefore specified.

2. Apparatus for withdrawing aerated vapor and condensate from steam condensers, comprising a steam jet device in communication with a condenser, a receiver, a passage leading from the steam jet to the receiver, means for withdrawing aerated vapor and water separately from said receiver, said means comprising a reciprocating pump, a passage leading from the lower portion of the receiver to an end of said reciprocating pump and another passage leading from the receiver to the other end of 20 said reciprocating pump, a pump connected to the condenser, and a passage for conveying water discharged from said pump to the passage last mentioned and to said receiver, the whole as and for the purpose hereinbefore specified.

3. Apparatus for withdrawing aerated vapor and condensate from steam condensers, comprising a steam jet device in communication with a condenser, a receiver, a passage leading from the steam jet to the receiver, means for withdrawing aerated vapor and water separately from said receiver, said means comprising two reciprocating pumps, a passage leading from the lower portion of the receiver to an end of 25 each of said reciprocating pumps, and passages leading from the receiver to the remaining ends of said reciprocating pumps, a pump connected to the condenser and a passage for conveying water discharged 30 from said pump to the passages last mentioned and to said receiver, the whole as and for the purpose hereinbefore specified.

4. Apparatus for withdrawing aerated vapor and condensate from steam condensers, comprising a steam jet device in com-

munication with a condenser, a receiver, a passage leading from the steam jet to the receiver, means for withdrawing aerated vapor and water separately from said receiver, said means comprising two vertical reciprocating pumps, a passage leading from the bottom of the receiver to the uppermost ends of each of said reciprocating pumps and passages leading from the upper part of the receiver to the remaining ends of 70 said reciprocating pumps, a pump connected to the condenser, and a passage for conveying water discharged from said pump to the passages last mentioned and to said receiver, the whole as and for the purpose 75 specified.

5. Apparatus for withdrawing aerated vapor and condensate from steam condensers, comprising a steam jet device in communication with a condenser, a receiver, a passage leading from the steam jet to the receiver, means for withdrawing aerated vapor and water separately from said receiver, said means comprising two vertical reciprocating pumps, a passage leading from the bottom of the receiver to the uppermost ends of each of said reciprocating pumps, and passages leading from the upper part of the receiver to the remaining ends of 80 said reciprocating pumps, a pump connected to the condenser, and a passage for conveying water discharged from said pump to the passages last mentioned and to said receiver, the whole as and for the purpose 85 specified.

6. In apparatus for withdrawing aerated vapor and water from steam condensers, comprising a steam jet, a receiver, pumping mechanism, separate passages for the withdrawal of the aerated vapor and water from 90 the receiver and passages for the delivery of a portion of the water discharged from the condenser to the receiver and of another portion of such water to the passage traversed by the aerated vapor after it has left the receiver, the whole as and for the purpose 95 hereinbefore specified.

7. In apparatus for withdrawing aerated vapor and water from steam condensers, comprising a steam jet, a receiver, a reciprocating pump, a passage for the withdrawal of aerated vapor from the receiver into one end of the barrel of said pump, a separate passage for the withdrawal of water from the receiver into the other end of said pump, and passages for the delivery of a portion of the water discharged from the condenser to the receiver and of another portion of such water to the passage traversed by the aerated vapor after it has left the receiver, the whole as and for the purpose 100 hereinbefore specified.

8. In apparatus for withdrawing aerated vapor and water from steam condensers, comprising a steam jet, a receiver, two re-

ciprocating pumps, passages for the withdrawal of aerated vapor from the receiver into one end of the barrel of each pump, a passage for the withdrawal of the water from the receiver into the remaining barrel ends, and passages for the delivery of a portion of the water discharged from the condenser to the receiver and of another portion of such water to the passages traversed by the aerated vapor after it has left the re-

ceiver, the whole as and for the purpose hereinbefore specified.

Signed at West Hartlepool, in the county of Durham, England, this eighteenth day of August, 1914.

DONALD BARNS MORISON.
